DISH RINSING RACK

Menroe L. Wexler, Chicago, Ill., assignor to Sears, Roebuck and Co., Chicago, Ill., a corporation of New York

Application September 3, 1937, Serial No. 162,257

4 Claims. (Cl. 141—9)

This invention relates to rinsing racks or baskets for dishes, silverware and the like.

An object of my invention is to provide a compact dish rinsing rack adapted to occupy minimum space in and out of use.

It is also an object to provide a rack for rinsing and draining dishes and the like which may be supported on a drainboard of a sink and which confines the rinse fluid to the sink.

A further object is to provide a device of the type referred to which, when not in use, is adapted to collapse.

Another object is to provide a sink cupboard and rinsing basket adapted to be stored therein with economy of space.

Further objects and advantages of this invention will appear as the description proceeds.

My invention is illustrated in the accompanying drawings, in which:

Fig. 1 is a side elevation of a basket or rack constructed in accordance with one form of the invention, ready for use.

Fig. 2 is a front elevation of the same.

Fig. 3 is a sectional view taken as indicated by the line 3—3 in Fig. 2.

Fig. 4 is a plan view of this device when collapsed.

Fig. 5 is a front elevation of the device when collapsed.

Fig. 6 is a transverse sectional view through a sink, cupboard and the device of Figs. 1 to 5 stored therein.

Referring now more particularly to the drawings, the rinse basket 9 appearing in Figs. 1 to 5 comprises an upstanding splash guard base frame 10, preferably of sheet metal, within which is supported, as by spot-welded brackets 11, a mesh wire floor 12 of any suitable formation. Dish supporting dividers 13 may be fastened to and extend above the floor. Projecting down preferably adjacent the corners of the floor are feet 14 which may be formed of rubber or other suitable material to grip the surface of a drain board 15 or other support.

The frame 10 is generally U-shaped, its ends 17 being turned in toward each other, leaving therebetween adequate space for ingress and egress of dish plates and the like. The top of the frame at the sides and front is preferably generally at a level adjacent that of the top of the dividers 13.

Side wall panels 18 are hinged at 20 to the sides 23 of the frame 10. Each side panel has a projecting part or lip 25 adjacent the hinge to engage the outside of the frame 10 and serve as a stop

to prevent the panel from swinging up past a substantially vertical position, where it constitutes in effect an extension of a side of the frame.

The rear wall 26 of the frame has an upwardly projecting portion 27 and a rear wall panel 28 is hinged thereto at 29.

The rear panel 28 has an intermediate lip 31 and end lips 32 engageable with the rear side of the frame extension 27, serving to prevent the panel 28 from swinging backward beyond a substantially vertical position, where it forms in effect a continuation of the frame extension 27. The ends 33 of the rear panel 28 are in the form of flanges bent forward and adapted to engage 15 the outer faces of the rear ends 35 of the side panels 18, serving thereby as bracing means therefor. The lower ends of the flanges 33 are continuations of the end lips 32, which project below the tops of the sides of the frame 10, affording end bracing for the rear panel so as to relieve the rear panel hinges 29 of axial stresses.

When the device is collapsed it appears as shown in Figs. 4 and 5, with the side panels 18 substantially horizontal, one resting on dividers 25 13 and the other lying thereover, and the rear panel 28 overlying the side panels and supported thereon by its flanges 33 engaging the middle lips 25 of the side panels. In Fig. 5 the rear panel is shown inclined forward and down, but 30 obviously by varying certain dimensions, as, for example, the width of the flanges 33, the rear panel may lie flat or at any desired inclination.

In opening the device, the rear panel 28 is first raised. The flanges 33 thereof carry spring 35 catches 37 having rounded displaceable portions 38 which, when the rear panel is upright, project slightly forward of the rear edges 39 of the side panels. As each side panel is swung to upright position, its rear edge 39 snaps by the 40 rounded spring portion 38 and is thereafter held assembled with the rear panel as shown in Figs. 1, 2 and 3.

The top edge of the rear panel, the top and 45 front edges of the side panels, as the three panels appear when upright, and portions of the top and front edges of the frame 10 are rolled smooth as shown at 41 for safety in handling and improved appearance. These rolled edges on the side panels 50 are adapted to abut the rolled edges on the flanges 33 as shown at 42, when the lips 31 and 32 on the rear panel engage the back of the frame 10, so as to hold the rear panel firmly in upright position. The spring catches of the rear panel 55 then cooperate with the lips 25 in holding the

side panels 18 upright. Thus the panels mutually, in cooperation with the frame 10, maintain one another upright and provide an operatively rigid casing or splash guard.

The panels may be lowered simply by swinging the side panels toward each other, snapping them free of the springs 37 in so doing, since thereafter the rear panel is free to be swung down over the side panels, whereupon the device is in collapsed condition. In this condition the device takes up very little room and may be easily stored out of the way in a cupboard or other suitable place.

When the basket 9 is not in use, it may be stored in a cupboard, and is particularly adapted for convenient disposition on the shelf 52 of a cupboard 53 below a sink 54, since the usual gooseneck or other drain pipe section 55 may project between the ends 17 of the frame 10 and well into the interior of the basket as shown in Fig. 6. If desired, additional utensils (not shown) may be stored in the basket in the space remaining between the drain pipe section 55 and the basket walls.

In the various forms of my invention, a rinse nozzle such as is commonly found as an accessory to modern sinks, may be introduced at the front of the rinse basket to rinse dishes and the like arranged therein, and the rinse water will be confined by the basket walls to the interior of the basket and will flow out of the bottom of the basket and into the sink sump.

In the various forms, also, the dividers 13 may include rubber or other suitable sheaths 13a, as shown in Fig. 6, to avoid the possibility of marring the articles to be supported by them.

I am aware that many changes may be made and details of construction varied through a wide range without departing from the principles of my invention, and I therefore do not purpose limiting the patent granted hereon otherwise than as necessitated by the prior art.

I claim:

1. A rack comprising a compartment having an open top, an openwork floor including means

forming the sole support for dishes, and a lateral opening relatively wide at the top to provide clearance for a dish sprayer and relatively narrow at the bottom to prevent outward escape of the sprayed water adjacent the ends of said opening at the floor.

2. A rack comprising a base, collapsible wall panels hinged to said base, means on said base and panels for preventing outward swing of said panels beyond substantially upright positions, and means on said panels for yieldably preventing inward collapse of said panels, the last mentioned means including a resilient member yieldable in response to inward manual force on one of said panels, said member being inoperative relative to said one panel when the latter is disposed inwardly of its outermost position.

3. A rack comprising a base, a pair of wall panels movably connected to said base, one of said panels having a spring and the other panel having a portion which may be forced past said spring selectively in either direction to connect and disconnect said panels, said panels affording mutual support for each other when said panels are connected, to maintain said panels upright, said spring being shiftable out of its normal position by said other panel in each direction of movement of said other panel.

4. A rack comprising a base, three wall panels hinged to three sides of said base, one of said panels being U-shaped and having its arms extending adjacent and toward the other two panels, springs on the inner faces of said arms for releasable connection with the adjacent ends of the other two panels when all of said panels are upright, to maintain said panels upright, and means for preventing outward movement of said U-shaped panel beyond its upright position, so that when said other two panels are raised they will become interlocked with said U-shaped panel, and when said other two panels are lowered they will become disconnected from said U-shaped panel.

MONROE L. WEXLER.
